AUTOMOBILE ASH TRAY

Filed Sept. 11, 1928

INVENTOR.

BY RAYMOND MORALES.
Munn & Co.

ATTORNEYS.

UNITED STATES PATENT OFFICE.

RAYMOND MORALES, OF SAN FRANCISCO, CALIFORNIA.

AUTOMOBILE ASH TRAY.

Application filed September 11, 1928. Serial No. 305,185.

The present invention relates to improvements in automobile ash trays and its principal object is to provide an ash tray for an automobile or other vehicle that is provided with a conduit leading ashes, cigarette stubs, etc. through the floor of the vehicle upon the road bed.

A further object of the invention is to provide a suitable yielding cover for this ash tray which allows cigarette stubs and the like to be urged therethrough and automatically closes again.

A further object of the invention is to provide a suitable lining for the ash tray that may be easily removed for the purpose of cleaning the same.

Further and other objects of the invention will appear as the specification proceeds.

The preferred form of my invention is illustrated in the accompanying drawing in which

Figure 1 shows a fragmentary sectional view through a vehicle body looking from the rear toward the steering wheel, with my ash tray attached thereto;

Figure 2, a vertical section through the ash tray, with a fragmentary view of the automobile body to which it is attached; and

Figure 3, a perspective detail view of a receptacle lining the ash tray.

While I have shown only the preferred form of my invention, I wish to have it understood that the same may be changed in various respects within the scope of the claim attached hereto without departing from the spirit of the invention.

In its preferred form, my ash tray comprises a preferably tapering receptacle 1 having a discharge conduit 2 extending downwardly from the bottom thereof. In the form selected, I show this ash tray as being fastened to one of the doors 3 of a vehicle body, but it should be understood that the same may be fastened to a fixed part of the body.

The fastening means comprises preferably two clips 4 passing around the conduit and fastened to the door by means of screws 6. Where the ash tray is fastened to the

within close proximity of the floor of the vehicle body and registers with a second conduit 7 provided in the floor when the door is closed. The second conduit 7 is curved rearwardly underneath the body of the vehicle as indicated in Figure 2.

It should be understood that when the ash tray is fastened to a fixed body of the vehicle, the two conduits may be joined into one.

To allow the ash tray to be cleaned conveniently, I use a cup-shaped lining 8 adapted to be fitted into the tray and corresponding to the form thereof.

On top of the ash tray, I provide two hinged gates 9 having springs 11 associated therewith which urge the gates upwardly to form a closure for the tray opening while suitable stops 12 prevent the gates from swinging beyond a horizontal position under the influence of the springs. It will be seen that when it is desired to drop ashes or a cigarette stub into the ash tray, the gates can be easily depressed to provide an opening for the article to be discharged into the tray.

The manner in which my tray may be used will be readily understood from the foregoing description. The ashes or cigarette stubs may be easily dropped through the hinged gates and the latter will automatically return to a closing position.

For the purpose of cleaning the ash tray, the lining 8 may be easily removed.

The break in the conduit allows the door to be opened, and when the door is closed, the ashes or cigarette stubs dropped into the ash tray will be automatically discharged upon the road bed.

I claim:

An ash tray of the character described having means associated therewith for fastening the same to the door of a vehicle body, a discharge conduit for the tray leading to the floor of the vehicle body and a conduit secured in the floor and extending downwardly therefrom and positioned to register with the first conduit when the door is closed.

RAYMOND MORALES.
